UNITED STATES PATENT OFFICE.

JOHN N. CONE, OF MINEVILLE, NEW YORK.

TRICYCLE-HORSE.

SPECIFICATION forming part of Letters Patent No. 601,555, dated March 29, 1898.

Application filed January 5, 1897. Serial No. 618,040. (No model.)

To all whom it may concern:

Be it known that I, JOHN N. CONE, a citizen of the United States, residing at Mineville, in the county of Essex and State of New York, have invented certain new and useful Improvements in Tricycle-Horses; and I do hereby declare the following to be a full, clear, and exact description of the invention, such as will enable others skilled in the art to which it appertains to make and use the same.

The invention consists of certain novel constructions, combinations, and arrangements of parts, which will be hereinafter more particularly set forth and claimed.

The invention also consists of certain other novel constructions, combinations, and arrangements of parts, all of which will be hereinafter more fully described and claimed.

In the accompanying drawings, forming part of this specification, Figure 1 represents a side elevation of a cycle embodying my invention. Fig. 2 represents a central vertical section through the same; and Fig. 3 represents a longitudinal horizontal section taken on the line $x-x$ of Fig. 2, looking downward.

A in the drawings represents the frame of the toy; B, the figure, which in the present instance is a horse; C, the driving-wheels, and D the steering-wheel. Said frame A may be of any desired construction and material, but is preferably a flat platform, as shown. The horse B may also be of any desired construction and material, but is preferably made of wood, as shown in the drawings, to represent as near as possible the outlines of a horse with the saddle, bridle, &c. The driving-wheels C are mounted upon the rear of the frame A in brackets a by means of a shaft a' . This shaft is mounted in ball-bearings secured to the lower ends of said brackets and is rigidly secured to one of the said wheels C, which latter are preferably provided with rubber tires. The shaft a' is provided with a sprocket-wheel a^2 , which communicates with another sprocket-wheel a^3 by means of a sprocket-chain a^4 . The sprocket-wheel a^3 is adjustably mounted in position upon spaced segmental rods a^5 , which have their respective ends secured to the under side of the horse and the upper side of the platform A. The said segments a^5 describe an arc the center of which is the sprocket-wheel a^2 , so that said sprocket-

wheel a^3 may be adjusted up or down upon the same to secure the desired adjustment of the cycle for children of different sizes without loosening or tightening the chain a^4 . The said wheel a^3 is mounted upon a crank-axle a^6 , which is journaled in suitable ball-bearings mounted upon an adjustable clamp a^7 , which clamp is provided with adjusting-screws a^8 , whereby it may be secured at any point upon the segmental rods a^5 . The outer end of the crank-axle a^6 is provided with the usual cranks a^9 and pedals a^{10} , whereby the driving-wheel C may be operated by the feet of the child seated upon the horse. The front or steering wheel D is mounted in the lower forked end f of a vertical shaft F, which latter is mounted in the platform A by means of a suitable ball-bearing f' . The said shaft F projects upward through the body of the horse B and is provided with a flat apertured head f^2 , that projects through an elongated slot f^3 , formed in the plate f^4 , secured to the under side of the head of the horse over a suitable recess f^5 , formed therein. The said apertured head f^2 is provided with a laterally-extending pin f^6 , whereby said head is prevented from passing out through the slot f^3 . The under side of the head of the horse is beveled in opposite directions from the shaft F, so that it may be rocked back and forth with the pin f^6 as a fulcrum, said pin permitting this movement, but preventing the head of the horse passing off the head f^4 . The said plate f^4 is provided with an auxiliary elongated slot f^7 , through which passes the end of a rod f^8 , the said rod being provided with a suitable laterally-projecting pin f^9 , similar to the pin f^6 , whereby the rod is prevented from withdrawing from said plate f^4 , but at the same time is allowed to rock back and forth therein as the head of the horse is turned. This rod f^8 passes through a guiding-bracket f^{10} , secured to the shaft F, and is connected at its lower end to an auxiliary rod f^{11} by means of a turn-buckle f^{12} . The office of this latter buckle is to lengthen or shorten the connection between the brake-shoe and the head of the horse, so as to get the desired pressure upon the former.

The lower end of the rod f^{11} is pivotally connected to a suitable brake-shoe f^{13} , pivoted between the bifurcated end of a screw-threaded stud f^{14} , mounted upon the fork f , so that

its free end will engage the tire upon the wheel D. A coil-spring f^{15} is mounted upon the rod f^8 between the bracket f^{10} and the turnbuckle f^{12} , so as to normally hold the head of the horse forward and the brake-shoe out of contact with the wheel D.

The rods f^8 and f^{11} turn with the rod F, as the same is operated by the turning of the horse's head to operate the steering-wheel, 10 said rods working through suitable segmental slots formed in the body of the horse and the platform A.

It will be observed from the foregoing description that when it is desired to turn the wheel D either to one side or the other the head of the horse is simply turned in the direction desired by pulling upon one or the other of the reins. Should it be desired to apply the brake, both sides of the reins are 20 pulled upon at the same time, thus turning the head of the horse back upon the fulcrum f^6 and operating the rods f^8 and f^{11} and applying the brake-shoe f^{13} . Upon the pressure being removed from the reins the head 25 of the horse will be automatically returned to its normal position by the spring f^{15} . It is desirable in a device of this character to have the guiding-wheel normally held straight, so that some little pressure is required to turn the same to one side or the other. To accomplish this, I provide the shaft F with an arm f^{16} , adjustably secured thereto by a screw-bolt f^{17} . The outer end of this 30 arm is bifurcated and provided with an anti-friction-wheel f^{18} . Two flat springs G are mounted within the horse upon opposite sides of a block g, so that their free ends project forward upon opposite sides of the antifriction-wheel f^{18} . By this construction when the 35 head of the horse is turned to one side or the other the said antifriction-wheel f^{18} engages either one or the other of the springs G and presses the same out of its normal position. It will thus be observed that the head of the 40 horse is held to one side under spring tension, and the moment the pressure is released the head will be turned to its normal straight position by the spring which is under tension.

Having thus described my invention, what

I claim as new, and desire to secure by Letters Patent, is—

1. The combination with a wheeled platform, of a figure mounted thereon and having a movable head, driving-wheels on said platform, a shaft journaled in the platform, and 55 connected at one end to the movable head, a steering-wheel at the opposite end of said shaft, a brake-shoe contiguous to one of the wheels, and a connection between said brake-shoe and the movable head, whereby the tipping of the head will effect an application of the brake-shoe, substantially as described.

2. In a toy cycle, the combination with a suitable platform, of an artificial horse mounted thereon and provided with a movable head, 60 driving-wheels mounted on said platform, a vertical shaft mounted on said platform and connected to the movable head at its upper end, a steering-wheel mounted on the lower end of said shaft, a brake-shoe mounted on 70 said shaft, and means connecting said brake-shoe to the movable head, whereby upon the tipping of the latter the brake is applied, substantially as described.

3. In a toy cycle, the combination with a 75 suitable supporting-platform, of an artificial horse mounted thereon and having a movable head, driving-wheels mounted under said platform, a vertical shaft mounted in said platform and adapted to support the movable head, so that the same may be turned from side to side and tipped back and forth, a guiding-wheel mounted at the lower end of said shaft, a brake-shoe pivotally mounted on said shaft and adapted to engage the periphery of 80 the guiding-wheel, and a spring-pressed rod connecting the movable head and said brake-shoe, whereby, upon the tipping of said head the brake is applied, and said head is returned to its normal position upon the pressure being removed, substantially as described.

In testimony whereof I have signed this specification in the presence of two subscribing witnesses.

JOHN N. CONE.
